UNITED STATES PATENT OFFICE.

CHARLES J. NECHAMKIN AND SAMUEL COHEN, OF BROOKLYN, NEW YORK.

AMUSEMENT DEVICE.

Application filed June 12, 1926. Serial No. 115,543.

Our invention relates to an amusement device, particularly to a device having its amusement features embodied in games to be played by children or adults; and more particularly to a device which on one face is provided with openings, representing the open mouths of clownheads, into which balls may be tossed and from which openings, by means of channels the balls may be led to other openings near the base of the device and there ring a bell and be permitted an exit from the device; and which on another face is provided with "moon" faces in which there is substituted for the nose a hook upon which a ring may be tossed; the device having on another of its sides a "score board" upon which the records of the participants in the game may be recorded; the device being of box-like formation formed so that the sides carrying the game features incline from the base upwardly toward each other, one side being removable and the whole device being so constructed that it will stand in operative position upon a base forming an integral part of the structure.

Some of the objects of our invention are, to provide a device of this character which shall be of comparatively few parts, of simple and compact construction, of cheap cost, which will retain itself in operative position for use without other support than its base which has embodied therein game features that are of novel character and have both amusement and educational value.

Another object is, to provide a device of this character that shall carry amusement or game features on opposite faces and shall provide means to record the score on another face.

Another object is, to provide a device of this character of substantially box-like construction, in which one of the game carrying faces of the structure is slidably removable from the structure, in order to permit ready access to the interior thereof when desired.

Another object is, to provide on one of the faces of the device a ball toss game comprising openings into which balls may be tossed and having means to carry the ball from said opening to other openings near the base of the structure so that the ball will ring a bell and register in a slot numbered correspondingly to the number of the opening into which the ball was originally tossed.

Another object is to provide hook devices

to represent the noses in the ring toss portion of our device, which may be detached from the device for convenience in shipment, or which may be readily attached thereto when the ring toss game is to be operated. 60

Another object is, to provide a structure of this character which shall be of box-like formation and of such form that the base thereof shall be substantially wider than the top and such that when the games are operated the structure will, of its own weight and because of this peculiar formation remain in operative position.

Another object is, to provide on the game carrying faces of our device designs forming 70 a part of the games which shall in combination with the mechanical features be of a comic character and of themselves be a means of amusement to children or others.

Our invention consists in the peculiar construction, combination, organization, and arrangement of parts shown in the accompanying drawings, described in the specification and more particularly pointed out in the appended claims. 75

In the drawings:

Fig. 1 is a front elevation of the front face of our device, showing the clown faces the arrangement of the apertures in the face, the ball as positioned in one of the outlets near 85 the base of our device, and in dotted lines, the arrangement of channels leading from the respective apertures to the corresponding exits and also in dotted lines the arrangement of the bells in reference to these exits. 90

Fig. 2 is an elevation of the rear face of our device, showing the arrangement of the ring toss game with the moon face design of figures and the detachable nose pieces thereon, and the detachable relation of this 95 side of our structure from the box-like body portion.

Fig. 3 is a side elevation, showing the hook like nose pieces of the ring toss game with a ring mounted thereon and with a score 100 board on one side of the structure.

Fig. 4 is a vertical cross-sectional view, taken on line 4—4, looking in the direction of the arrows, showing the arrangement of the apertures in the face carrying the ball-toss game, the relation thereto of the channelled guides and the bell provided in the base of the structure near the exits. 105

Fig. 5 is a top plan view, partly in cross section of the hook members in the ring toss 110

game, and the means by which these hook members are detachably held in operative relation therewith.

Fig. 6 is an enlarged view in elevation of 5 a hook member and means by which it is operatively carried in combination with the ring toss game.

Referring to the drawing, in which like numerals of reference indicate corresponding parts, our device comprises a substantially box-like body portion having a base 10, a front 11 and a rear 12, which front 11 and rear 12 extend upwardly from the base 10, incline toward each other and terminate 15 in a top portion 13, which is of lesser depth than the base 10. Extending substantially vertically upwardly from the base 10 to the top portion 13 are opposite lateral sides 14, which join the sides 11 and 12 and thereby 20 complete the formation of the substantially box-like structure.

The front face 11 is provided with a series 25 of illustrations of arbitrarily formed clown shaped faces 15, each showing an open mouth and each of which is in fact an aperture or opening 16 into which a ball or other like device may be tossed. Directly back of each of these openings 16 we provide a substantially U shaped channel or guide piece 17, 30 which guide pieces are inclosed within the interior of the box-like structure and at its upper end is affixed to the inner face of the side 11 and extends downwardly approximately to the base 10 where it terminates on 35 a sub base or shelf like portion 18, below and back of exit openings 19, to which the ball may be guided by the channel 17 and out of which it may be taken for repeated use after the operator has succeeded in tossing the ball 40 into one or another of the openings 16.

The sub-base or shelf 18 is provided with an opening in its body portion near each exit or opening 19, and is supported in operative position substantially parallel to the base of 45 the portion 10 by having one end attached to the inner face of an outstanding substantially vertical portion 21 at or near the lower end of the face 11 and by having its other end supported by a downwardly extending 50 leg 22, connecting with the sub-base 18 and affixed to the inner face of the base 10. The sub-base 18 thereby also serves as a stop for the ball after it has been tossed into the aperture 16 and been directed to the lower end of 55 the channel 17.

Below the sub-base 18, carried on the base 10 we provide a bell, or sound producing device 23, extending upwardly from which, through the opening 20 in the sub-base 18 is 60 a plunger 24, which plunger 24 is so positioned and arranged that it is in the path of travel of the ball as it reaches the lower end of the guide 17. The ball therefore is caused to strike the plunger 24 and ring the bell 23, 65 and then the ball will register in one of the

exits 19 corresponding in number or count to that of the aperture or mouth opening 16 into which it was tossed and from which it was led by the channel member 17. These channel guides 17 connect each aperture in 70 the clown faces to a corresponding aperture near the base; and each clown face is designated by a different numeral or valuation, which corresponds to the designating numeral or valuation indicated above one or 75 another of the exits in the lower portion of the front face of the device.

It will be seen therefore that as the ball toss game is played and a ball is tossed into the mouth opening 16 in the clown face the 80 ball will disappear in the mouth and pass down the channel 17 connected to the opening 16 and appear in the exit 19, when it will ring the bell 23 positioned under that exit 19, and will then be stopped by the stop 85 21 and there retained in position to be removed for further use in the game. The channel member 17 being of substantially U shaped formation is so positioned in reference to the rear of the face 11, that the face 90 11 closes the open portion of the channel member 17, and thereby forms a substantially four sided closed guide or channel, to direct and control the course of the ball from the mouth opening 16 to the corresponding 95 exit 19 and the bell 23.

The channel members 17 are so attached to the sub-base 18 and the rear face of the front portion 11 of our device that they may be 100 readily detached therefrom for repair or other purposes, and are so disposed in operative position in reference to the mouth openings and the exits, that while these respective openings are each provided with an independent channel member and bell, the 105 channel member and bells are enclosed within the box-like structure of our device and are hidden from view.

The game provided on the rear face 12 of the box-like structure is so arranged that 110 each arbitrarily designed or moon shaped face illustration is given a different designating number or value and is provided with a detachable hook-like portion 25, representative of a nose. This hook-like portion 25 is designed to receive and hold a ring 115 26 which may be tossed and caught thereon. The hook-like portion 25 is carried on or affixed to a base or plate 27, which is retained in detachable but operative position to the moon shaped face or figure or the face 12 of the box-like structure by means of a clamp 28. The clamp 28 is formed in substantially a single piece and is provided with opposite jaw-like portions 29 and a jaw like portion 30 joining the lower ends of the opposite jaw like portions 29, the jaw like portions 29 and 30 being angularly bent slightly from the body portion of the clamp 28 sufficiently to receive back thereof and between these jaws 120 300

29 and 30 and the face 12 of this side of our structure, the plate like portion 27, carrying the bent hook portion 25. This arrangement is provided so that the hook like portion may 5 be mounted in or demounted from their operable positions if it is desired.

The face 12 upon which the ring toss game is carried is detachable from the box-like body portion of our structure. This relation 10 is made possible by providing on the opposite edges 31 and 32 of the opposite sides 14 of the box-like body portion, flange portions 33 and 34, which are inwardly bent toward each other and on the base 10 a flange portion 35, upwardly bent from the base portion 10, and which together with the flange portions 33 and 34 are arranged to engage and 15 position the face 12 and hold it in operative but slideable relation to the box-like body portion, in order to permit its removal when desired, for access to the interior of the box-like body portion, if for repairs or other 20 reason such access is desirable.

On one of the vertical sides 14 we provide 25 a schedule or score board, as is shown at 36, upon which may be made the record of the scores of the various players in the game.

It will be seen therefore, that we have 30 provided a device which is of unique design, of compact construction, which embodies amusement and educational features, which is so arranged that it retains itself in position for use without other support than the base of its box-like body portion, which is 35 arranged so that a plurality of different games may be played thereon by different sets of players, and which is provided, integral with its body portion, with means upon which a score or record of the score of 40 the various players may be kept, and which also, while substantially of closed box-like formation, is nevertheless so designed that access may readily be had to the interior thereof by means of a removable sliding face, 45 when it is desired for purposes of repair or other reasons to have such access, which is provided with sound producing means to register a hit or successful toss of a ball to notify a player of the fact that a score has 50 been made, which is provided with parts detachable and removable from the box-like structure to facilitate the convenient shipping and transportation of the device and to effect a ready assembling or disassembling 55 thereof, and which has other advantages and results, some of which may be obvious from the foregoing specifications.

We may fashion our box like structure of 60 wood, metal, papier-mâché, or any other suitable material having sufficient strength and rigidity for the purpose for which it is designed, and we may likewise fashion our channel members of wood or other suitable material, and may provide sound producing 65 means of any desirable character, such that

they will be operated when the ball has come to rest in the exit compartments heretofore described, and we may provide the game carrying faces of our device with any arbitrarily chosen suitable illustrations or figures 70 in place of the clown heads or moon shaped illustrations.

Having thus shown and specifically described our invention in detail we do not wish to be limited thereby, except as the 75 state of the art or appended claims may require, for it is obvious that various modifications and changes may be made in the particular combination, organization, arrangement, and construction of parts of our 80 invention, without departing from the spirit and scope thereof.

What we claim as new and desire to secure by Letters Patent is:

1. In a device of the character described, 85 the combination of a substantially hollow structure having two opposite upwardly extending inclined sides, one of said sides being detachable therefrom, a series of apertures in one of said sides, guide members 90 within said structure connecting said apertures, sound producing means disposed within said guide members, hook means detachably arranged upon the outer face of said detachable side, and record receiving means 95 disposed on a third side of said structure.

2. In a device of the character described, the combination of a substantially hollow structure having two opposite upwardly extending inclined sides, one of said sides being detachable therefrom, a series of apertures in one of said sides, guide members 100 within said structure connecting said apertures, sound producing means disposed within said guide members, hook means detachably arranged upon the outer face of said detachable side, record receiving means disposed on a third side of said structure, means adapted to be received into the apertures of 105 said body portion and actuate said sound producing means, and ring means adapted 110 to be carried upon said hook means.

3. In a device of the character described, the combination of a box-like structure, having a pair of opposite substantially vertical 115 faces, a series of apertures in the body portion of one of said faces, a series of apertures near the base of said apertured face, guides connecting said apertures in said body portion with said apertures near the 120 base thereof, a series of hooked members on the body portion of the other of said faces, and substantially vertical sides connecting said opposite faces to form a substantially 125 box-like structure.

4. In a device of the character described, the combination of a box-like structure, having a pair of opposite substantially vertical faces, a series of apertures in the body portion of one of said faces, a series of aper-

tures near the base of said apertured face, channelled guides connecting said apertures in said body portion with said apertures near the base thereof, a series of sound producing members arranged in said apertures near said base, a series of hook members on the body portion of the other of said faces, and substantially vertical sides connecting said opposite faces to form a substantially box-like structure.

5. In a device of the character described, the combination of a box-like structure having a pair of substantially vertically inclined faces, a series of apertures in the body portion of one of said faces, a series of apertures near the base of said apertured face, channelled guides connecting said apertures in said body portions with said apertures near the base thereof, a series of hooked members on the body portion of the other of said faces, and substantially vertical sides connecting said inclined faces, to form a substantially box-like structure.

6. In a device of the character described, the combination of a box-like structure having a pair of opposite substantially vertical faces, a series of apertures in the body portion of one of said faces, a series of apertures transversely arranged across the body portion of said apertured face near the base thereof, channelled guides connecting said apertures in said body portion with said apertures near the base thereof, a series of sound producing members arranged below said channel guides adapted to be actuated from said apertures near said base, a series of hook members on the body portion of the other of said faces, substantially vertical sides connecting said opposite faces, and a top connecting said vertical sides and said opposite faces, to form a substantially box-like structure.

7. In a device of the character described, the combination of a box-like structure having a pair of opposite substantially vertical faces, a series of apertures in the body portion of one of said faces, a series of apertures transversely arranged across the body portion of said apertured face near the base thereof, channelled guides connecting said apertures in said body portion with said apertures near the base thereof, a series of sound producing members arranged below said channelled guides adapted to be actuated from said apertures near said base, a series of hook members on the body portion of the other of said faces, substantially vertical sides connecting said opposite faces, a top connecting said vertical sides and said opposite faces, and a base connecting said opposite faces and sides, to form a substantially closed box-like structure.

8. In a device of the character described, the combination of a box-like structure hav-

ing a pair of opposite substantially vertically inclined faces, one of said inclined faces being slidably detachable from said box-like structure, a series of apertures in the body portion of the other inclined face, a series of apertures near the base of said last mentioned face, guide members connecting said apertures in said body portion with said apertures near the base of said apertured face, a series of hook members on the body portion of the detachable face, substantially vertical sides connecting said inclined faces, a base connecting said inclined faces and said vertical sides, and a top connecting said inclined faces and said vertical sides, to form a substantially closed box-like structure.

9. In a device of the character described, the combination of a box-like structure substantially of the shape of a truncated pyramid having a detachable side, a series of apertures in the body portion of a nondetachable side, a series of apertures near the base of said nondetachable side, guide members connecting said body portion apertures with side base apertures, means to detachably hold said guide members in operative position, sound producing means disposed at the base of said guide members within said box-like body portion, means extending into said guide members adapted to actuate said sound producing means, hook members detachably carried on the outer base of said detachable side of said box-like structure, and record receiving means provided on a third face of said box-like structure.

10. In a device of the character described, the combination of a box-like structure having a pair of opposite substantially vertically inclined faces, a series of substantially circular apertures in the body portion of one of said faces, a series of substantially rectangular apertures near the base of said apertured face, guide members connecting said substantially circular apertures with said rectangular apertures, means to detachably hold said guide members in operative position within said box-like structure, a sound producing member disposed at the lower end of said guide member, means extending through said guide member adapted to effect the actuation of said sound producing means, a series of hook members detachably mounted on the body portion of the other of said faces, substantially vertical sides connecting said inclined faces, and a base connecting said inclined faces and said vertical sides, to form a substantially hollow box-like structure.

Signed at the city of New York, in the county of New York and State of New York this tenth day of June, A. D. 1926.

CHARLES J. NECHAMKIN.
SAMUEL COHEN.
